FLY ASH ENTRAPMENT WALL

Ernest L. Daman, Westfield, N.J., assignor to Foster Wheeler Corporation, New York, N.Y., a corporation of New York

Filed July 19, 1961, Ser. No. 125,245

4 Claims. (Cl. 122—235)

This invention relates to furnaces. It is a fly ash entrapment means especially suitable for the combustion of slag forming fuels.

In furnaces for use with slag forming fuels, it is generally considered desirable that the amount of fly ash carried by combustion gases from the combustion zone to the convection zone be kept to a minimum. Furthermore, it is advantageous to dispose of the ash in a fused state. Toward these ends, relatively cool surfaces are provided in the combustion zone. The flame stream is directed onto the cool surfaces so that slag resulting from combustion will freeze thereon. Fuel particles adhere to the slag. Oxygen in the combustion gases flowing over the slag, scrubs the fuel to oxidize combustible materials therein. As the slag layer thickens, slag remote from the surface melts forming a slag stream which migrates down the surface under gravity thereby effecting the removal of non-combustibles in liquid form.

Relatively ash-free combustion gases are now obtained by means of cyclone furnaces wherein a high velocity is imparted to a mixture of fuel air and combustion gases. The flame stream is directed to sweep a relatively cool cylindrical surface whereon a slag stream develops.

Inherently, cyclone furnaces have operating problems which must be lived with. Extremely high operating temperatures liberate many more substances from coal than are usually vaporized in combustion. Precipitation of some of these substances in the convection zone is particularly onerous. Also it is necessary to impart very high air velocities, at a significant expenditure in energy, to retain the slag on the walls of the cyclone. It is in these disturbing consequences that the desire to minimize fly ash carry over and excessive air pressure is rooted.

The present invention avoids this difficulty by a novel furnace arrangement. More particularly, a plurality of burners are disposed to direct flame stream including fuel and air over a cooled target wall disposed in spaced relationship relative to the burners. The target wall describes a plurality of undulations including troughs disposed vertically in the combustion chamber for receiving a mixture of fuel and combustion gases and causing the mixture to pass in sweeping relationship relative to the target wall to develop a slag stream.

Basically, this advance offers a furnace for slag forming fuels which accommodates conventional burners operated at usual-coal-burning temperatures and air pressures. With cool-burning the offensive effects of fly ash carry over are obviated. Whatever fly ash which might escape into the convection zone can be returned to the target wall for entrapment in the molten slag so that dry fly ash disposal may be virtually eliminated. Additionally, the plural burner arrangement affords uniform slagging characteristics over a wide range of furnace load.

These and other advantages will appear more fully from the detailed description viewed in conjunction with the accompanying drawings with the same number designation for analogous elements throughout the various views and wherein:

FIGURE 1 is an elevation view in vertical section of a reheat boiler embodying this invention.

FIGURE 2 is a sectional view taken along line 2—2 of FIGURE 1 and showing the relationship of the zig-zag target wall to the burners.

FIGURE 2A is comparable to FIGURE 2 and shows

2

a second species with the burners spaced for oblique incidence of the flame relative the target wall.

FIGURE 3 is an enlarged detail taken on line 3—3 of FIGURE 1.

FIGURE 4 shows the invention adapted to a conventional industrial boiler.

FIGURE 5 is a sectional view on an enlarged scale taken along line 5—5 of FIGURE 4.

FIGURE 6 is a vertical section of a cylindrical boiler embodying another form of this invention.

FIGURE 7 is a sectional view taken along line 7—7 of FIGURE 6.

In FIGURES 1 and 2, furnace housing 11 defines a rectangular combustion chamber. First compartment 12 and second compartment 14 are defined in housing 11 by longitudinal target wall 16 and are communicated by passage means 17. Second compartment 14 is serially arranged relative to convection section 18 and flue 19 which provide means for removal of combustion gases from the chamber.

Burners communicate with a source of pulverized fuel and a source of oxygen (neither of which are shown). Burners are divided into a first portion 23 which direct their flame streams transversely into first compartment 12 and a second portion 24 which direct their flame streams transversely into second compartment 14.

Fly Ash Entrapment

Means for fly ash entrapment are shown as target wall 16. Means for cooling target wall 16 are shown as tubes 26 from which ceramic material 27 depends. The cooling means maintains the target wall below the freezing (fusion) temperature of the non-combustible fly ash material so that slag will freeze on the wall.

Undulations of target wall 16 provide troughs 28 on the first compartment side which alternates with troughs 29 on the second compartment side thereof. Each of the troughs 28, 29 are arranged to receive flame comprising a mixture of fuel oxygen and combustion gases from at least one of the burners 23, 24. The burners can be arranged to intercept the troughs either normally bisecting troughs 28, 29 as shown in FIGURE 2 or obliquely relative target wall 16 as shown in FIGURE 2A. The flame stream courses around the trough in sweeping relationship relative target wall 16 thereby depositing a coating of frozen slag 31. Fuel particles stick to the slag 31 and are scrubbed by oxygen which sweeps by in the flame.

As the layer of slag 31 builds up, slag remote from the target wall becomes hotter because of the insulating quality of the fly ash material preventing the flow of heat to tubes 26. When a sufficient coating 31 of slag has been established, the slag remote from target wall 16 melts and flows downward under gravity. Means for exhausting molten slag are shown as ports 32.

Recirculation of Dry Fly Ash

Collection means which can take the form of a dry fly ash precipitator (not shown) are employed to recover the portion of dry fly ash which escapes past the fly ash entrainment means. Conduit means return the dry fly ash to port 30 for reinjection into compartment 12. By recirculation of dry fly ash, virtually all of the non-combustible material becomes entrapped into molten slag 31. Clinker which forms on cooling the molten slag is useful as a lightweight construction aggregate. In this regard, the removal of even a small fraction of the non-combustibles as dry fly ash is often a major operating problem.

Superheater Regulation

Superheater regulation means shown in FIGURE 1 comprises dampers 35 which are well-known in the art operatively connected to first group of burners 23 and

second group of the burners 24. By regulating the flow through first 23 and second 24 burners, respectively, the rate of flow through passage means 17 may be determined. In this manner, the degree of effectiveness of a superheater or reheater 33 may be controlled.

Tubes 26 forming target wall 16 also form division wall 34 and are opened to define screens 36 which serve as passage means 17. Of course, arrangements are possible wherein convection sections could be provided on both sides of the furnace housing in instances where greater superheater or reheater space is required.

The embodiment shown in FIGURES 4 and 5 has only a single compartment 12 and is fired from only one side. Target wall 16 is disposed closer to the burners than it would be in a conventional boiler. Above target wall 16, rear wall 37 slopes back to provide transition into conventional furnace cross-section above the ash separating zone.

As shown in FIGURES 6 and 7, this invention is also adaptable to cylindrical boilers. This feature would be of particular interest for supercharged designs since it would permit inclusion of the stress distribution advantages available with cylindrical shells.

It will be understood by those familiar with the furnace art that wide changes may be made in the details of construction and the correlation of the various elements of this fly ash entrainment means without departing from the scope of the invention as defined by the claims.

What is claimed is:

1. In a furnace including a housing which defines a combustion chamber, means for exhausting combustion gases from the chamber; the combination comprising a burner having a longitudinal axis; sources of slag forming coal and oxygen communicating with the burner, the burner disposed to direct a burning slag forming coal stream into the chamber; a means for fly ash entrainment comprising a target wall in the chamber; means for cooling the target wall below the freezing temperature of non-combustible material in said coal stream; the target wall describing an upright trough having converging side walls joined along the narrow portion of the trough and an area in the wide portion of the trough substantially greater than the cross-sectional area of said stream; the trough diverging towards the burner and being disposed in spaced relationship with the burner approximately perpendicular to the burner axis, in the path of the stream of flame and coal from the burner, causing the stream to approximately horizontally course the upright walls of the trough in sweeping relationship therewith coating the trough with molten slag, the molten slag migrating down the trough and trapping coal particles from the stream of flame and coal for brushing engagement with oxygen in the stream; and means for exhausting molten slag from the trough.

2. In a furnace including a housing which defines a combustion chamber, means for exhausting combustion gases from the chamber; the combination comprising a burner having a longitudinal axis; sources of slag forming coal and oxygen communicating with the burner, the burner disposed to direct a burning slag forming coal stream into the chamber; a means for fly ash entrainment comprising a target wall of a ceramic material disposed in the chamber; the target wall describing an up-

right trough having converging side walls joined along the narrow portion of the trough and an area in the wide portion of the trough substantially greater than the cross sectional area of said stream; the trough diverging towards the burner and being disposed in spaced relationship with the burner approximately perpendicular to the burner axis, in the path of the stream of flame and coal from the burner, causing the stream to approximately horizontally course the upright walls of the trough in sweeping relationship therewith coating the trough with molten slag; means for cooling the target wall arranged to maintain the target wall below the fusion temperature of the slag causing an innermost layer of the slag to freeze, an outermost molten layer migrating down the trough; the molten layer trapping coal particles from the stream of flame and coal for brushing engagement with oxygen in the stream; and means for exhausting molten slag from the trough.

3. In a furnace for the combustion of a slag forming coal having a substantial portion of non-combustible material, with the furnace including a housing which defines a combustion chamber, means for exhausting combustion gases from the chamber; the combination comprising a plurality of burners each having a longitudinal axis; sources of oxygen and slag forming coal communicating with each burner, each burner disposed to direct a burning slag forming coal stream into the chamber; a means for fly ash entrainment comprising a target wall disposed in the chamber; the target wall describing a plurality of undulations including upright troughs each having converging side walls joined along the narrow portion of the trough and an area in the wide portion of the trough substantially greater than the cross-sectional area of the burner streams; the troughs diverging towards the burners and being disposed in spaced relationship with the burners approximately perpendicular to the burner axes, in the paths of the streams of flame and coal from the burners; means for cooling the target wall below the freezing temperature of non-combustible material in said coal streams; at least two of the troughs each arranged for receiving a stream of flame and coal from at least one of the burners causing the stream to approximately horizontally course the upright walls of that trough in sweeping relationship therewith coating the trough with molten slag, the molten slag migrating down the trough and trapping coal particles from the stream of flame and coal for brushing engagement with oxygen in the stream; and means for exhausting molten slag from the troughs.

4. The combination of claim 3 wherein said troughs have top and bottom walls defining ends for the troughs, the streams of flame and coal also coursing said top and bottom walls.
